UNITED STATES PATENT OFFICE.

CHARLES LEFKOWITZ, OF NEWARK, NEW JERSEY.

CARBOY.

Original application filed March 30, 1923. Serial No. 628,877. Divided and this application filed January 5, 1924, Serial No. 684,636.

To all whom it may concern:

Be it known that I, CHARLES LEFKOWITZ, a citizen of the United States, and a resident of the city of Newark, in the county 5 of Essex and State of New Jersey, have invented a new Carboy, of which the following is a full, clear, and exact description.

My invention has for its object to provide 10 a carboy with a body having a vertically extending guide-ways in which lateral supporting members are disposed, the lateral supporting members being removable from the body and being constructed in a manner 15 which will, without great trouble, permit of the replacement of any part of the lateral supporting member which may be broken in service.

Another object of the invention is to construct 20 the lateral supporting members in a manner which will give the greatest possible strength and resiliency at the least possible expense.

Additional objects of the invention will 25 appear in the following specification in which the preferred form of my invention is described:

In the drawings similar reference characters refer to similar parts in all the views 30 in which,—

Fig. 1 is a perspective view showing my invention;

Fig. 2 is a perspective view of the cushioning bottom used in the carboy;

Fig. 3 is a view showing in elevation one 35 of the lateral supporting members which may be used in the carboy;

Fig. 4 is a side view of Fig. 3;

Fig. 5 is a view showing another form of 40 a lateral supporting member;

Fig. 6 is a side view of Fig. 5;

Fig. 7 is still another form of a lateral supporting member;

Fig. 8 is a side view of Fig. 7; and

Fig. 9 is a fragmentary view showing 45 another construction for holding the lateral supporting members in the body.

This is a division of the United States application filed on March 30, 1923 under 50 Serial No. 628,877.

By referring to the drawings it will be seen that the body 10, shown in the dotted lines in Fig. 1 of the drawings may be of crate construction, but it will be understood

that any other form of construction may be 55 employed. Disposed in the body 10 and secured to the sides thereof, there are standards 11 having guide-ways 12. The standards are vertically disposed in the guide-ways 12 and also extend vertically, the 60 guide-ways 12 having their openings disposed obliquely as shown in Fig. 1 of the drawings. In these guide-ways 12 the lateral supporting members 13 are disposed, these lateral supporting members having 65 horizontal members 14, the edges of which fit in the guide-ways 12, these horizontal members 14 being preferably spaced apart and being connected by the vertically extending members 15. The vertically extending members 15 are preferably secured 70 to the inner sides of the horizontally extending members 14 so that the bottle will rest against the vertically extending members 15. 75

These lateral supporting members 13 may be laminated and in Figs. 3, 4, 5, 6, 7 and 8 are shown forms in which the lateral supporting members may be constructed in a laminated manner. In Figs. 3 and 4 is 80 shown a lateral supporting member 13^a having horizontal members 14^a spaced apart which are connected by vertically extending members 15^a. The horizontal members 14^a are laminated as illustrated in Fig. 4 85 of the drawings. Preferably only one part of the horizontal laminated members has its ends disposed in the guide-ways 12 but it will of course be understood that all the parts of the horizontal laminated members 90 may have their ends disposed in the said guide-ways.

In the construction of the lateral supporting member illustrated in Figs. 5 and 6, the horizontal laminated members 14^a are 95 not spaced apart and they are arranged as shown in the drawings and are connected by the vertically extending members 15^b.

In the construction shown in Figs. 7 and 8 the horizontal laminated members 14^c are 100 narrower than are the horizontal laminated members 14^a, the horizontal laminated members 14^c being spaced apart as illustrated and being connected by the vertically extending members 15^c. 105

In Fig. 3 of the drawings the guide-ways are not made in the standard 11^a but to the said standard 11^a, guides 16 are secured,

these guides 16 having guide-ways 12^a in which the ends of the horizontally extending members 14 are disposed.

Referring to Fig. 2 of the drawings it will be seen that the cushioning bottom illustrated is provided with horizontally extending resilient members 17 spaced apart which as shown, are substantially parallel to each other. The ends of these resilient members 17 are held above the bottom of the carboy by the supports 18. Disposed at an angle to the resilient members 17, there are resilient members 19 which are held above the bottom of the carboy by supports 20.

Having thus described my invention what I claim as new and desire to protect by Letters Patent is:

1. In a carboy, a body vertical standards spaced apart and secured in the body, the standards having vertical guideways with oblique openings, and obliquely extending lateral supporting members in the body with side edges disposed in the guideways.
2. In a carboy, an angular body, pairs of vertical guideways with oblique openings disposed in the body between its corners and obliquely extending lateral supporting members in the body with their side edges disposed in the guideways.
3. In a carboy a body having guide-ways, horizontally disposed laminated members

having portions removably disposed in the guide-ways and vertical members to which the laminated members are secured.

35

4. In a carboy a body having guide-ways horizontally disposed, cushioning members with their ends disposed in the guide-ways and vertical contact members secured to the cushioning members.

40

5. In a carboy, a body having vertical guideways with substantially parallel sides, supporting members disposed in the guideways for limited movement in the guideways, and vertical members connecting the supporting members for reinforcing the supporting members, the vertical members engaging at their edges a bottle when disposed in the carboy.

45

6. In a carboy, a body, standards disposed in the body and having vertical guideways with oblique openings, each guideway having two substantially parallel sides spaced apart, and obliquely extending lateral supporting members disposed in the guideways and supported by the said sides of the guideways.

50

7. In a carboy, a body having vertical guideways, horizontal laminated members disposed in the guideways, and vertical members connecting the laminated members for reinforcing the laminated members, the vertical members engaging at their edges a bottle when disposed in the carboy.

55

CHARLES LEFKOWITZ.
